2,659,971

TOOTH FACING AND BACKING THEREFOR

Ado Vecchiotti, Ascoli Piceno, Italy

Application February 25, 1948, Serial No. 10,768

Claims priority, application Italy
February 20, 1948

1 Claim. (Cl. 32—9)

1

The present invention relates to improvements in the interchangeable facing for dental prothesis and in the devices for the anchorage thereof upon the backing.

The interchangeable facings actually known cover only the front face of the teeth (incisive teeth, and canine teeth) leaving thus visible a metal contour on the incisive surface. As a matter of fact either the metallic incisive margin in the prothesis used to be constructed purposely longer than the facing, in order to prevent the incisive margin, of the latter, from being broken, or the incisive margin of the facing was totally protected with metal, to a great advantage of the strength but to the detriment of the aesthetics.

It is an object of the present invention to provide a facing, made either of synthetic resins or of china, wherein the metallic elements actually present, after the application of the prosthetic apparatus, are invisible, since the whole incisive surface and a portion of the rear surface (in the proximity of the incisive margin) are formed either of a synthetic resin or of porcelain, having a color similar to that of the natural teeth.

Another object of this invention is to provide a plurality of anchorages to fit the facing onto the backing, in such a way that the resulting artificial tooth is very strong and adapted to withstand the strain due to mastication.

In one practical embodiment of the present invention, the facing, besides having the usual socket serving for the anchorage of the facing onto the frontal post of the backing, is provided with a metallic reinforcing plate protecting the less resistant parts and strengthening also the white material whereof the facing is made. Upon the said plate is welded a reversely bent plate secured at one end to the incisal end of the reinforcing plate and having its free end forming a projection for entering a recess formed in the metal body, to which the backing is welded, and adjacent the said backing.

In a modified form of construction of the facing, the reinforcement of the facing is reduced to a pivot having a right angle bent portion embedded in the material of the incisal portion of the facing, which pivot is adapted to be received in the recess formed in the metallic body adjacent to the backing welded to the said body.

In a further practical embodiment, the facing is made exclusively either of china or synthetic resin and has no metallic reinforcement. The facing is provided with a socket for receiving a post on the backing and is also provided with a slot in the heel portion of the facing to receive

2

a portion of the backing plate. In addition, a second socket is provided opening into the slot for receiving a projection carried by the backing plate.

5 The various forms of practical embodiment of the facing are illustrated in the annexed drawing wherein:

Figure 1 represents a vertical section both of the facing and of the backing, according to one 10 form of practical embodiment;

Figure 2 represents a rear view of the facing showing the metal plate applied thereto;

Figure 3 represents a transverse section on the line III—III of Figure 2 of the metal plate fitted 15 on to the facing;

Figure 4 represents a vertical section of the facing according to a second form of practical embodiment;

Figure 5 represents a view of the backing where 20 the facing of Figure 4 is to be fitted;

Figure 6 represents a perspective view of another form of practical embodiment of the facing;

Figure 7 is a vertical section on the line 25 VII—VII of Figure 6;

Figure 8 is a vertical section of the backing on which the facing of Figs. 6 and 7 is to be fitted;

Figure 9 is a front elevation of the backing of Fig. 8;

30 Figures 10 and 11 represent the side view of two different types of backings carrying a thin metal plate welded to its rear surface.

Referring now to Figures 1—3 of the drawing, the artificial tooth is composed of a backing 1, which is welded to a metallic body 2 and of an interchangeable facing 3, which may be detachably fitted on the backing. Facing 3 comprises a non-metallic element provided with a cylindrical socket 4, extending from the base towards the incisive edge over a length equal to about two thirds of the length of the facing. Such cylindrical socket opens on the rear of the facing. The socket is lined with a metal plate 5, which covers also a portion of the rear surface 35 of the facing. Said plate is provided with two lateral bent projections 6 which penetrate in the mass of the white material constituting the facing. On the rear portion of plate 5 is welded a thin plate 8 which, in its lower portion, is spaced from the said plate 5, in such a way as to form an interstice wherein the upper portion of backing 1 may be introduced. For this purpose, adjacent to the rear of the backing a recess 9 is formed in the metallic body 2 to which the backing is welded.

55 The backing 1 is provided with a post 10 in-

tended to penetrate into the metal lined socket 4 of the facing.

Both the plate 5 and the plate 8, which act as anchorage members, are provided with holes 7 for a more efficient connection with the mass of white material of facing 3.

From Figure 1, it may be seen how the facing 3 and the backing 1 are capable of being approached and caused to slide to each other, in such a way as to effect the introduction of the post 10 into the metal lined socket 4 and the introduction of plate 8 into the recess 9, thus insuring a fast connection between facing and backing.

In the form of practical embodiment shown in Figure 4, the reinforcing plate is reduced to a reinforcing element in the form of a pivot 12, of cross-sections embedded in the upper part of the facing 11 and bent to a right angle, which pivot projects from the base of the heel 13 for engaging the recess 14 provided between the backing 15 and the metallic body 16.

In the form of practical embodiment of Figures 6 and 7 the facing 17, besides the cylindrical socket 18, is provided, inside the heel 19, with a horizontal slot 20, extending through the whole width of the facing and open at the two sides of the same. A socket 32, of rectangular section, is provided in the central portion of the facing and opens into said slot.

The backing 21, which carries on its anterior surface the post 22, projects beyond the upper surface of the metallic body 25. The outermost portion of the backing is in the form of a pivot 23 of rectangular cross section provided with a groove 24. For coupling the facing 17 with the backing 21, the post 22 is introduced in the socket 18, pivot 23 in the socket 32 and the portion 28 of the backing in the slot 20. This form of practical embodiment affords the advantage of having three anchorages and of permitting the use of the common backing available in the trade.

Figures 10 and 11 represent two types of backing in which, instead of making use of a metallic body welded to the backing, a thin metal plate is provided, such as 26 or 27, bent to an angle and welded to the backing. Such a thin plate acts as a shoulder or support for the backing.

From the drawing it may be seen that the anterior surface of the facing, its incisal surface 29, the incisal angles 30 and a portion of the surface of heel 31, near the incisal surface, may be entirely formed either of synthetic resin or of porcelain so as to visibly conceal at every point the metal in the mouth.

The facing of this invention is fixed to the backing, as usual, by means of cement. Should

any breakage of the facing accidentally occur, the latter may easily be replaced even without removing the prothesis apparatus from the mouth.

Having thus described the invention, what I

claim is:

A device of the character described comprising an interchangeable tooth facing having an incisal end, a backing therefor and a metallic body to which the said backing is welded, said facing comprising a non-metallic body having a longitudinally extending socket therein opening on the rear surface of the facing, said facing having an overhanging portion at the incisal end thereof and provided with a transverse slot extending the whole width of the facing and open at the two sides of the same, the lower surface of the overhanging portion of the facing being flat to rest on the upper surface of the said metallic body, said overhanging portion of the facing being further provided with a socket of rectangular cross section opening into the said slot and having a width less than the width of the slot, said socket of rectangular cross section being positioned rearwardly of the longitudinal socket on said facing, said backing having the upper part toward the incisal end of the facing projecting beyond the said metallic body to which it is welded, the said projecting part of the backing comprising a lower portion having a width equal to the width of the facing and arranged to penetrate in the said transverse slot of the overhanging portion of the facing and an upper portion having a width less than the width of the backing and being in the form of a pivot of rectangular cross section, having a recess in each side edge thereof, the said pivot being positioned to enter the said socket of rectangular cross section in said overhanging portion of the facing and a longitudinally extending post carried by the backing for entering the longitudinal socket on said facing, whereby the connection of the tooth facing with the backing therefor is effected by three separate engagements.

ADO VECCHIOTTI.
